APRON

Marjorie R. Basinais Daley, 2692 11th St.,
Cuyahoga Falls, Ohio 43219

Filed Apr. 30, 1973, Ser. No. 355,579

Term of patent 14 years

Int. Cl. D2—07

U.S. Cl. D2—227

FIG. 3

FIG. 2

FIG. 1

FIG. 5

FIG. 6

FIG. 4

FIG. 1 is a front perspective view of an apron showing my new design;

FIG. 2 is a front perspective view thereof with the overlay portion removed;

FIG. 3 is a front perspective view of the overlay portion of my design;

FIG. 4 is a front perspective view of a second embodiment of the design of FIG. 1;

FIG. 5 is a perspective view of the belt portion thereof in an opened position; and

FIG. 6 is a perspective view of the second embodiment with the belt removed.

I claim:

The ornamental design for an apron, as shown and described.
